UNITED STATES PATENT OFFICE

2,448,081

AUTOMATIC AMMUNITION FEED FOR FIREARMS

Woodville B. Conway, Escondido, Calif.

Application July 20, 1944, Serial No. 545,755

7 Claims. (Cl. 42—17)

1

The present invention relates to firearms and has particular reference to firearms in which cartridges are fed in succession to the firing chamber from a magazine containing a large quantity of cartridges. This successive feeding of the cartridges to the firing chamber may be accomplished manually or automatically. Therefore, the invention herein described is applicable to firearms in which some part is operated manually to cause a succession of cartridges to be fed into the firing chamber as well as to automatic or semi-automatic firearms which utilize the energy of recoil, or of the explosion gases of the cartridge, to feed a succession of cartridges to the firing chamber.

The present invention has among its objects the provision of a firearm with a magazine which runs parallel with the barrel of the firearm and in which cartridges packed in standard sized cartons, containing two rows of cartridges, may be transferred directly from the box to the magazine, regardless whether all the cartridges in the cartons are arranged with their bullet ends all pointing in one direction or whether some of the cartridges have their bullets pointing in one direction and others have their bullets pointing in the opposite direction.

The present invention also has among its objects the provision of comparatively simple means for rendering firearms operative upon a succession of single cartridges fed from a comparatively large source of supply of the cartridges conveniently and simply carried on the firearm.

Further objects are either specifically pointed out in the description given below or are evident therefrom.

The accompanying drawings illustrate a rifle embodying the invention which is particularly suited for 45 caliber ammunition of the type now used in pistols and carbines. In these drawings wherein the same reference character, in the several views, indicate the same or corresponding part,

Figure 1 is a side elevation of the right side of the rifle with the portion of the stock at the rear of the trigger guard omitted and the front end of the barrel broken away.

Figure 2 is a plan view of the parts shown in Figure 1.

Figure 3 is a central vertical longitudinal section of the rifle illustrated in Figures 1 and 2 at the battery position of the bolt, the lever 116 supported by the bolt.

Figure 4 is a view of a portion of Figure 3 showing the position of parts during a different stage

2

of their operations at cocked position, the lever 116 being at initial lowered position.

Figure 5 is a perspective view of a portion of the means used for turning a cartridge, which is about to be inserted into the firing chamber, from a position in which the direction of the longitudinal axis of the cartridge is perpendicular to direction of the longitudinal axis of the bore of the barrel to the position in which the bullet end of the cartridge points towards the firing chamber.

Figure 6 is a top plan view of the magazine which may be used in a rifle constructed according to the present invention.

15 Figure 7 is a central vertical longitudinal section of the magazine shown in plan in Figure 6.

Figure 8 is a cross-section on the line 8—8 of Figure 7.

15 Figure 9 is a cross-section on the line 9—9 of Figure 6 on a larger scale.

The rifle illustrated in the accompanying drawings comprises a stock 2, a housing or receiver 3 carried by the said stock, a barrel 4 having a bore 5, a bolt 6 reciprocable in said housing, a magazine 7, and other parts referred to hereinafter.

The bolt 6 is provided with a lug 10 near its rear end. This lug passes outwardly through the slot 11 in housing 3 and a knob 12 is attached to said lug to serve as a handle for manually operating the bolt. Bolt 6 has been shown more or less schematically in the drawings, since the essence of the present invention does not lie in details of bolt construction; and since any suitable bolt including a firing pin, extractor mechanism

30 for fired cartridges, and other parts of bolt mechanisms, may be used. Bolt 6 reciprocates in longitudinal opening 13 in housing 3.

Barrel 4, in the embodiment of the invention shown, is in screw thread engagement with the 40 housing 3, and at its rear end is provided with a chamber 14 in which the cartridge is ultimately received or placed for firing.

To the rear of firing chamber 14, and somewhat spaced therefrom is a cartridge turning or 45 orienting member 15, which, cooperating with parts hereinafter described, serves to turn a cartridge, about to be inserted in the firing chamber, from a position in which the direction of its longitudinal axis is perpendicular to the direction of

50 the longitudinal axis of the bore 5 to a position in which the bullet end of the cartridge points to or is headed towards the firing chamber 14. The structure and operation of cartridge turning member 15 is described hereinafter.

55 Immediately to the rear of cartridge turning

member 15 is a space 16 (see Fig. 4) within the housing 3, this space constituting a receiving chamber for a cartridge 17 which is conducted into the said receiving chamber from the supply of cartridges 18 in the magazine 7.

An elevator 20 (see Figs. 3 and 4) raises the cartridges from the throat end of the magazine 7 into the receiving chamber 16 behind the turning member 15. This elevator is carried at the forward end of a lever 21, pivoted on the pintle 22 carried between the spaced sides 23 and 24 of the housing 3. The rear end of lever 21 is provided with an arcuate cam surface 25 which is engaged by the under side of bolt 6, when bolt 6 is brought into the retracted position. The rear end of the lever 21 is urged to rotate clockwise by a spiral spring 26 which extends from a socket 27 in the lever into a socket 28 in a portion of housing 3. When the bolt 6 is retracted, its lower part engages the cam surface 25 and causes lever 21 to be rotated counter-clockwise to raise elevator 20 between sides 23 and 24 of housing 3, from the position shown in Figure 3 to the position shown in Figure 4. Stops 29 and 30, carried by the housing 3, limit the extent of the downward and upward movement of lever 21 and, as a consequence, the extent of possible upward and downward movement of elevator 20 is also determined by said stops.

Magazine 7 extends substantially parallel with and beneath barrel 4, and comprises a channel portion consisting of top 35, a bottom 36, and a back 37. The right hand side wall and slide front 38 of the magazine consists of a slide which is guided in grooves 39 and 40 provided in top 35 and bottom 36 respectively. This front slide 38 is attached to a head 41 at the forward end of the magazine and extends rearwardly to a point 42 where it abuts against the side wall 43 of the throat of the magazine. The front slide 38 is provided with a slot 44 which extends from near the rear end 45 thereof to near the front end 46 thereof, as shown in Figure 1. This slot receives a pin or stud 78 movable along the slot, and attached to a follower 60 within the magazine as hereinafter explained.

The construction of the rear or throat end of the magazine is illustrated in Figures 3, 4, 6, 7 and 9. The throat of the magazine is formed by side walls 43, wall 37' (being a continuation of back 37), top inclined portion 50, bottom inclined portion 51 (the latter two being convergent to a spaced relation equal to the diameter of a cartridge), end portions 52, and bottom portions 53. Bottom portions 53 and end portions 52 are spaced apart in order to provide an opening 54 for the passage of elevator 20. Walls 37, 43 and 52 extend upwardly from the bottom portions 53 flush with the top 35 of the magazine and are so disposed as to form a vertical well 55 through which the cartridges are conducted from the magazine into receiving chamber 16 (see Figs. 3 and 4) by the upward motion of elevator 20. The inclined portions 50 and 51 of the throat of the magazine are respectively provided with grooves 56 and 57 within which respectively slide fins 58 and 59 carried by a follower 60.

Follower 60 is a hollow member, and comprises inwardly and forwardly divergent inclined portions 64 which are joined by a forwardly and upwardly inclined rearward end 65 the vertical extent of which is somewhat more than one third the height of the magazine chamber and located midheight therein. A cup-like rear portion 66 receives the follower spring 67 and is so formed and

fixed to the inclined portions 64 as to provide a shoulder 68, which interiorly affords a seat for the spring 67, and exteriorly serves as a keeper for a latch 71 to be described. An abutment for the spring 67 is provided by a depending flange 69 of the top 35 of the magazine. The rear portion 66 of the follower slidingly engages the top, bottom, left and front slide walls of the magazine for a distance sufficient to support the projected rear end 65 midway of the height of the magazine. The inclined portions 64 and the inclined rearward end 65 extend entirely across the magazine as shown in Figure 8. The fins 58 and 59 slide within the grooves 56 and 57 respectively when the follower 60 enters the throat end of the magazine.

The head 41 of the magazine carries a blade 70 which slides along the bottom 36 of the magazine and lying beneath the follower 60, passing in the space between the spring abutment 69 and the bottom 36 of the magazine. The follower 60 is held in the retracted position shown in Figure 7 by the engagement of shoulder 68 by latch 71 which is carried by leaf spring 72 secured by means of screws 73 to the top 35 of the magazine. As shown in Figure 7 the latch 71 passes through an opening in the top 35 of the magazine to engage shoulder 68 of the follower. The forward end 74 of leaf spring 72 is curved upwardly, so that a releasing bar 75, which is secured to head 41 by screws 76 (see Figs. 6 and 7) may pass under and lift leaf spring 72 to clear the shoulder 68 when the head 41 of the magazine slide 38 is fully closed against the forward end of the magazine. When latch 71 releases the follower, the follower is urged towards the throat end of the magazine by means of spring 67, whereby cartridges within the magazine are pressed towards and into the throat thereof, as shown, for example, in Figures 3 and 4.

The stud 78 which passes through slot 44 of front 38 of the magazine may be provided with a knurled knob or head 79 as a handgrip for retracting the follower. Assuming that the magazine does not contain any cartridges, and that the head 41 of the magazine is closed, the pin 78 is then near or in contact with the rear end 45 of the slot 44. Now when the head 41 is pulled outwardly to move the sliding front 38, and thereby open the magazine, the end 45 of the slot engages the pin 78 of the follower and pulls the follower 60, against the action of spring 67, to the forward end of the magazine where it is latched in position by engagement of the latch 71 against the shoulder 68 of the follower.

The width, depth and length of the magazine are so selected that with the open side of the magazine downward or vertical or nearly vertical, one or more boxes of cartridges (after removal of the tops of the boxes) may now be inserted (without removal of the cartridges from the boxes) into the now open side of the magazine, with the closed bottom of the cartridge box towards the front of the magazine, the front being that side of the magazine that is closed by the sliding front 38. After the cartridges and cartridge boxes have been so placed in the magazine, the gun is tilted or laid horizontal with the open side of the magazine uppermost, and the boxes are lifted out of the magazine while permitting the cartridges to remain in the magazine. Sufficient clearance is provided in the magazine in order to permit the boxes to be easily lifted from the cartridges which remain behind in the magazine by force of gravity. As has been in-

dicated above, it is not necessary that the bullet ends of all the cartridges point in the same direction in the magazine, since the operative parts of the gun are such that some cartridges may be disposed with their bullet ends adjacent the front 38 of the magazine while the remainder have their bullet ends adjacent the back 31 of the magazine.

After the cartridges have been inserted in the magazine, the head 41 thereof is pushed inwardly of the magazine until said head engages the abutment 69. As head 41 moves inwardly, the sliding front 38 of the magazine moves therewith and closes the front of the magazine while sliding relatively to the pin 78 on the follower 60 owing to the sliding fit between said pin and the slot 44 in the front 38 of the magazine. Shortly before the head 41 reaches its final closed position, the bar 75 slides under leaf spring 72, thereby raising it and disengaging keeper 71 from shoulder 68 on the follower, whereupon the compression in spring 67 urges the follower 60 against the cartridges and presses them towards the rear or throat end of the magazine. In Figures 3 and 4 are shown a few cartridges being pressed towards the throat of the magazine. These few cartridges may represent some that have remained in the magazine after previous firing, starting with a magazine fully loaded, for example loaded with two boxes (40 rounds) of .45 caliber cartridges.

The magazine 7, as indicated above, and as shown in Figures 1 to 4, is located below the rifle barrel and parallel to the bore thereof. The throat end of the magazine is withdrawably inserted in housing 3, and rests as shown in Figures 3 and 4 on horizontal shoulders 81 provided on sides 23 and 24 of said housing. Vertical interior shoulders 82 (Figs. 3 and 4) on sides 23 and 24 limit the extent to which the throat of the magazine may be inserted within the housing 3. The shoulders 81 and 82 are so positioned that well 55 of the throat end of the magazine lies immediately below and registers with an opening 83 (behind the turning member 15) which leads into receiving chamber 16. A downwardly inclined plane surface 81a extends from each of horizontal shoulders 81 to the edge of each of sides 23 and 24 for the purpose of facilitating the assembly of the magazine with the other parts of the rifle as shown in Figures 3 and 4.

The blade 70 described above, and illustrated in Figures 3, 4, 7 and 8 extends from a shoulder 84 at the foot of inclined portion 51 to the opposite end of the magazine when the head 41, and front 38 attached thereto, are in the closed position. The part of the distance between the top 35 and bottom 36 that is filled in by the thickness of blade 70 is required in order to be able to insert the cartridges, while in their boxes, in the magazine between top 35 and bottom 36. When head 41 is moved to close the magazine, the blade 70 readily slides below the two rows of cartridges. The thickness of blade 70 is therefore about double the maximum wall thickness of the cartridge boxes.

The magazine is secured in the position shown in Figures 3 and 4 by suitable latching means. This latching means (see Figs. 1, 2, 6 and 7) may comprise a forwardly extending lug 85 carried below the barrel by band 86 secured to barrel 4. This lug is engaged by the swinging latch 87 pivoted at 88 on the top of magazine 7. Latch 87 is pulled towards the rear by means of a spiral spring 89, which is connected at one end with

latch 87 and at the other end with top 35 of the magazine. The top of the magazine 35 (see Figs. 6 and 7) is provided with a stop 90 fixed thereon, against which the rear end of the lug 85 abuts when the magazine is in latching position. This prevents accidental withdrawal of the magazine from the housing 3 before release of the latch 87. The swinging latch 87 is provided with a recess 91 within which forward end of the lug 85 fits when the rear end of the lug 85 is in abutting position against the forward part of stop 90.

The bottom 36 of the magazine 7 (see Fig. 1) may have secured to it in any suitable manner a hand grip or forestock piece 92 for use in supporting the rifle when it is being aimed.

Referring now more particularly to the cartridge turning means illustrated in Figures 1 to 5 inclusive. This means consists of a turning member 15 (shown in perspective in Figure 5) and means indicated generally by the numeral 100, the latter for imparting a forward thrust intermediate the ends of a cartridge when it is in position before the turning member 15 as shown in Figure 4.

Turning member 15 consists of a rectangular block set in the housing body 3 from above and having two grooved portions 101 and 102 which are spaced apart parallel with each other, with their grooves facing each other. Grooved parts 101 and 102 may be joined together at their bottoms by a web 103. Holes 104 near the front end of grooved portions 101 and 102 accommodate screws 105 (see Figs. 3 and 4) for securing member 15 in position in the housing 3. The said grooves decrease in depth from rear to front as shown in Figure 5, their bottoms being essentially arcuate surfaces, with their concavities facing each other, and having the same radius from respective parallel vertical axes adjacent to the rear bottoms of the opposite grooves. The width of the grooves measured from points 108 and 109 is less than the diameter of the primer end of the cartridge. In the case of center fire rimless cartridges having extracting grooves, the distance from points 108 and 109 should be a little less than the diameter of the base of the cartridge case. The grooves are of substantially uniform vertical width throughout their length and depth except at and near their rearward ends 110 where they may be flared or widened in order to facilitate the entry of bullets and turning of the cartridges. The space between the innermost walls of groove portions 101 and 102 is sufficient to permit the passage of cartridges through turning member 15 after they have been turned to a position in which their bullet ends point towards the firing chamber 14. The width of each of the grooves is great enough to permit the bullet end of a cartridge to enter either of the grooves while the primer end of such cartridge is held against entering the other groove, owing to the fact that the width of the groove is less than the diameter of such primer end. The arcuate bottom portions of the grooves serve to guide the bullet ends of the cartridges as they are being turned. The distance between the rearward ends of the arcuate portions is obviously to be chosen in accordance with the overall length of the cartridge.

When a cartridge is elevated by elevator 20 into the position occupied by cartridge 11 in Figure 4, the cartridge is engaged midway between its ends by the arcuate portion 115 of lever or finger 116. At this time the arcuate portion 115 extends forwardly above the cartridge and also

downward to the rear of it as shown in Figure 4. Lever 116 extends upward and rearward and is pivoted at 117 to the forward end of a slide 118 which is mounted to reciprocate in guide 119, on the top of housing 3. Another lever 120 is pivoted to the rear end of the slide 118 at 121. The free ends of each of levers 116 and 120 enter the housing 3, as shown in Figures 3 and 4, through suitable slots permitting the levers to move above the housing. Lever 116 (see Figs. 1 and 2) carries fixed thereon at each side cams 122 which are constructed and arranged to coat when lever 116 moves forward, with cams 123 transversely spaced and fixed on the top of housing 3. Lever 116 is pressed downward by leaf spring 124 secured to guide 119 by screw 125 or other suitable means. A notch with a shoulder 128 (see Figs. 3 and 4) is provided on bolt 6 for engagement with the rear end 129 of lever 120 when bolt 6 is in the fully retracted position. The housing 3 is provided with a slanting cam surface 130 with which an inclined portion 131 of lever 120 engages in order to disengage end 129 of lever 120 from shoulder 128 when lever 120 and connected parts are being moved forwardly by the early part of forward motion of the bolt.

A spiral spring 132 is attached at one end to lever 120 and at the other end to housing 3 and pulls said lever 120 together with slide 118 and lever 116 towards the rear or butt end of the rifle.

Operation.—The magazine is filled with cartridges as described above, some of these cartridges being indicated by the numeral 18 in Figures 3 and 4. When bolt 6 is retracted lever 21 rotates counterclockwise owing to depression of cam 25 by bolt 6. This counterclockwise rotation causes elevator 20 to rise from the position shown in Figure 3 to the position shown in Figure 4, thereby removing a cartridge from the throat of the magazine and placing it transversely in receiving chamber 16 behind cartridge turning member 15. It then constitutes cartridge 17 (see Fig. 4) in the receiver or receiving chamber 16, and is ready to be turned so that its bullet end points towards the firing chamber 14.

When bolt 6 is in the fully retracted position the rear end 129 of lever 120 is held by spring 132 down and in front of shoulder 128 in a notch on the bolt. As the bolt moves forward towards the turning member 15, lever 120, slide 118 and lever 116 are carried with it. The forward motion of lever 116 pushes against the cartridge 17 midway between its ends and causes its primer end to be blocked at the entrance to one of the grooves 101—102 and permits its bullet end to swing through the other one of these grooves, as before described. As the lever 116 continues to move towards the turning member 15, cams 122, carried by lever 116, ride on cams 123, whereby lever 116 rises to lift its end 115 out of the path of the forwardly moving bolt which pushes against the primer end of the now turned cartridge until it is seated in the firing chamber 14 ready to be fired. When end 115 of lever 116 has been raised out of the path of the advancing bolt 6, the said bolt continues to advance while end 115 of lever 116 rides on the top of the bolt as in Fig. 3. After the lever 116 has thrust the cartridge forward in turned position in the turning member 15, and has risen out of the path of bolt 6 (as described above), inclined surface 131 on lever 120 rides on cam surface 130 on housing 3, disengaging lever 120 from the shoulder 128 of the bolt, whereupon spring 132 pulls lever 120

together with slide 118 and lever 116 to the rear until the rear end of cams 122 (see Figs. 1 and 2) strike the guide 119 to arrest the rearward motion. The parts are now in the position shown in Figure 3. When the bolt 6 is again retracted in the further firing of the rifle, the shoulder 128 on the bolt again engages behind the end 129 of lever 120 and the operation is repeated. As will be seen from an inspection of Figure 3, when the bolt 6 has driven the cartridge into the firing chamber 14, the lever 21 has rotated so as to lower elevator 20 below the next cartridge in the throat of the magazine, and it is ready for a repetition of the loading operations already described.

15 I claim:

1. In a firearm, the combination of a receiver, a barrel attached thereto, coaxial receiving and firing chambers in said receiver and said barrel, respectively, a reciprocating bolt in said receiver, 20 an elongated cartridge magazine parallel to the barrel and attached to said receiver, means to deliver cartridges singly from said magazine to a position beneath the receiving chamber transverse to said barrel, an elevator lever pivoted 25 rearwardly of and to said receiving chamber having a cartridge-engaging part moveable vertically behind the mouth of said receiving chamber from a low position under a delivered cartridge at the magazine to engage and elevate 30 such cartridge to position with the engaged cartridge extended crosswise of the receiving chamber, said bolt being moveable from a cocked position to the rear of such cartridge through the receiving chamber to a battery position, said lever 35 having a cam thereon rearwardly of its pivot, spring means between said receiver and said lever urging said lever cam into the path of and rearward of the bolt when the latter is at battery position, and means cooperative with the bolt to 40 orient the elevated cartridge bullet end forwardly for loading engagement of the round in said firing chamber by said bolt on movement of the same to battery position.

2. The structure of claim 1 wherein the last 45 named means comprises a slide over the receiver, a lever device thereon moveable to and from engagement with the bolt at cocked position of the bolt and over a part of initial movement of the latter, means to disengage the 50 lever device from the bolt at a predetermined position of the bolt, under forward movement of the latter, a pushing finger pivoted on the slide extended forwardly and moveable into and from said receiving chamber and having 55 a part constructed and arranged to engage intermediately of the length of said cartridge at the receiving chamber, during a part of forward movement of the bolt, said finger being moveable above the chamber by the bolt and 60 means to selectively retard the base of said crosswise cartridge in said chamber.

3. The structure of claim 1 wherein the last 65 named means comprises a spring loaded slide over the receiver, a latch lever device thereon moveable to and from engagement with the bolt at cocked position of the bolt and over a part of initial forward movement of the latter, means to disengage the latch lever device at a predetermined position of the bolt, under forward movement of the latter, a pushing finger pivoted on the slide extended forwardly and moveable into and from said receiving chamber and having a part 70 constructed and arranged to engage intermediately of the length of said cartridge at the receiving chamber, during a part of forward move-

ment of the bolt, and means to elevate the finger at the forward limit of its movement, said finger being spring loaded and yieldable to said bolt.

4. The structure of claim 1 wherein the last named means comprises a slide over the receiver, a lever pivoted thereon extended rearward and downward moveable into and from the path of the bolt, the bolt having a shoulder thereon, said lever having an end spring pressed toward said path to engage said shoulder, said receiver having a wiper part thereon to engage and elevate said lever after a predetermined movement from said initial position, and spring means to return said lever and slide to initial position.

5. The structure of claim 1, wherein said receiving chamber includes a well part for an elevated transverse cartridge and having longitudinal walls extended forward therefrom and spaced apart less than the length of a cartridge, affording an opening in the top of the receiver, said walls having channels therein with their bottoms spaced more than the length of a cartridge, a slide longitudinally reciprocable over the receiver, a spring loaded operating lever pivoted thereon extended rearwardly moveable into and out of the path of the bolt and constructed to engage the same when at cocked position for movement therewith, means to release the lever at a predetermined forward position of the bolt, a pusher finger pivoted on the slide extended forwardly, spring urged into the receiving chamber rearward of said grooves, and having parts to engage behind and over said elevated cartridge in alignment with the space between said walls and moveable into said space under engagement of the first named lever by the moving bolt, and cam and wiper devices on the said finger and receiver constructed to fend said finger upward between said walls under forward movement of the finger.

6. In a firearm including a firing chamber, a magazine, feeding means for conveying a cartridge from said magazine to said chamber, and a cartridge turning means interposed between said magazine and said chamber to receive a transversely arranged cartridge including members spaced vertically to the transverse cartridge less than the base diameter of a cartridge and more than a predetermined part of the cartridge nose, and spaced longitudinally of such cartridge less than its length, and means to support a cartridge at a level with the last named means; the improvement comprising a U-shaped finger part normally disposed in a position to receive a transverse cartridge from said magazine between the arms of said U-shaped part, means coupling said finger to said feeding means to move therewith and move said cartridge to said cartridge turning means, means coacting with said finger and said feeding means for lifting said finger away from said cartridge after said cartridge is moved into said cartridge turning means, means operated by said feeding means for disconnecting said finger from said feeding means, and spring means normally urging said finger to said normal position.

7. In a firearm, the combination of a barrel having a firing chamber, a receiver attached to said barrel and having a receiving chamber, a bolt reciprocable in said receiver from a battery position at said firing chamber to a cocked position

rearwardly of said receiving chamber, a magazine of elongated form parallel to said barrel and attached to said receiver, said magazine being shaped to hold a plurality of cartridges in close packed relation with their axes transverse to an axial plane common to said barrel and magazine, said magazine having a delivery mouth for passing single cartridges, means to deliver cartridges singly from said mouth, an elevator lever pivoted to said receiver rearwardly of said receiving chamber and extending forwardly of said receiver and having an elevator at its forward extremity, said magazine having an opening formed through the mouth thereof registering with an opening in said receiver to form a well for the passage of the transversely arranged cartridges singly to said receiving chamber, said elevator being arranged to move through said openings from a normal position below the well, said lever having a cam member thereon rearwardly of its pivot in the path of said bolt for engagement thereby and adapted to be depressed thereby on rearward movement of said bolt to operate the elevator, spring means urging the lever cam into the path of said bolt, a slide longitudinally reciprocable on the receiver, a lever pivoted on the rear end of said slide having an end adapted to be moved into the path of said bolt, spring means attached to said receiver and to the rear end of said lever pivoted in said slide for retracting the lever rearwardly and into the path of said bolt, said bolt having a notch for engaging the end of said lever to propel the same forwardly with said bolt, cam means on said receiver for camming said lever outwardly to clear said bolt at a predetermined distance of the same from battery position, a projecting finger pivoted on the forward end of said slide and moveable into and out of said receiving chamber and transversely moveable therealong, said projecting finger being constructed and arranged to receive thereagainst an elevated transverse cartridge at retracted position of the slide to propel the cartridge forwardly and ahead of said bolt under forward movement of the same, and means in said receiver rearwardly of said firing chamber adapted to engage and orient the cartridge so propelled to turn its bullet in alignment with said barrel, said movement of the slide from retracted position to the cleared position of said lever being less than the movement of the bolt from cocked position to the oriented cartridge.

WOODVILLE B. CONWAY.
